(57) **CLAIM**

The ornamental design for a foot for a stick vacuum, as shown and described.

DESCRIPTION

FIG. 1 is a front perspective view of a foot for a stick vacuum which embodies our design;

FIG. 2 is a front view thereof;

FIG. 3 is a rear view thereof;

FIG. 4 is a left side view thereof, the right side being a mirror image; and,

FIG. 5 is a top view thereof.

The bottom view is unornamented.

The details shown in broken lines form no part of the claimed design.
